[57] CLAIM

The ornamental design for a cover for a tobacco container, as shown and described.

DESCRIPTION

FIG. 1 is a perspective view of a cover for a tobacco container showing my new design;

FIG. 2 is a top view thereof;

FIG. 3 is a side elevational view thereof with the sides at 120° being mirror images;

FIG. 4 is a front elevational view thereof with the sides at 120° being mirror images;

FIG. 5 is a bottom view thereof; and,

FIG. 6 is a fragmented sectional view taken along line 6—6 of FIG. 2.
